VENTING AND DRAINING MEANS FOR
PUMPSFrederick Walter McCombie, London, England,
assignor to Megator Pumps & Compressors
Limited, Feltham, EnglandApplication July 30, 1947, Serial No. 764,827
In Great Britain September 11, 1946

6 Claims. (Cl. 103—203)

1

This invention relates to pumps for delivering liquids and other than of the centrifugal type, an example of such a pump being that disclosed by the specification and drawings of British Patent No. 592,432.

In order to retain liquid in pumps of the non-centrifugal type for lubrication and sealing of the working parts, it is known practice for the inlet and outlet branches to be situated at or near the top of the pump so that air or vapour drawn into the pump may be readily expelled and so that the liquid in the pump will not drain out when the pump is stationary. A disadvantage of this arrangement is that the liquid resting in the lower portion of the pump may remain relatively stagnant while the pump is working and that solid matter carried in suspension in the liquid may be deposited in the lower portion of the pump instead of being carried away by the flow of liquid. The object of the invention is to provide means by which stagnation and deposition of solids in the bottom part of a pump of the non-centrifugal type may be avoided whilst still arranging the inlet and outlet at or near the top of the pump for the reasons already stated.

A pump of the non-centrifugal type is characterized, according to the invention, by the provision of a passage leading from the lower part of the pump to the outlet, the upper part of the pump being also connected with said outlet, either directly or through the medium of said passage, so as to permit the escape of air or vapour from the upper part of the pump casing out of the pump outlet and the upward flow of at least a part of the liquid and any solid matter which might otherwise accumulate in the lower part of the pump, along the passage and out of the pump outlet. Owing to the greater fluidity of air or vapour as compared with that of liquids, the opening from the upper part of the pump to the outlet may be of smaller cross sectional area than the passage leading from the lower portion, thereby causing the greater part of the liquid to pass to the outlet through the lower part of the pump casing and up the passage to the outlet while still providing ample area to pass the maximum volume of air or vapour that is liable to enter the pump.

The aforesaid passage may be an external pipe or may be formed integrally with the pump casing or with the aid of a separate deflector or baffle located in position within the pump casing.

In order that the invention may be clearly understood and readily carried into effect the invention is hereinafter described with reference to the accompanying drawings in which:

Figure 1 is a sectional view of a pump modified in accordance with the present invention;

Figures 2 and 3 are further sectional views il-

lustrating diagrammatically two alternative constructions.

Figure 1 illustrates by way of example the invention applied to the type of pump disclosed by the specification and drawings of British Patent No. 592,432, the pump comprising a casing 1 forming a pressure chamber fitted with a cover 2 the interior of which constitutes the suction chamber, a partition wall 3 being interposed between the two chambers. The pressure branch which is indicated by reference numeral 4 is connected directly with the pressure chamber 1, the suction branch (not shown) being connected with the interior of the cover 2. The rotor comprises a shaft 5 carrying eccentrics 6 and 6a angularly offset to give uniform delivery, each eccentric being arranged in a displacement chamber 7 of a width and depth such that the eccentric fits closely therein. On shaft 5 being rotated, the displacement chambers 7 will be displaced in a vertical plane, the displacement chambers being maintained in rubbing contact with a plate 8 under the pressure of the fluid in the pressure chamber, springs 9 being provided to maintain rubbing contact while pressure is being built up in the pressure chamber. Ports 10, 11, 12 and 13 are formed in the plate 8, ports 10 and 12 leading directly to the suction chamber while ports 11 and 13 lead through ducts 11a and 13a respectively in the partition wall 3.

As the eccentric shaft rotates in a clockwise direction, eccentric 6 alternately enlarges and reduces the volume of displacement chamber 7 and simultaneously moves the displacement chamber up and down so as to connect the displacement chamber alternately to suction or inlet ports 10, 12 and to outlet or delivery ports 11, 13 leading into the pressure chamber through ducts 11a and 13a. In this way liquid enters displacement chamber 7 from the suction chamber formed by cover 2 and is forced into the pressure chamber. Eccentric 6a operates in the same manner.

According to one embodiment of the invention the casing 1 contains a separately formed deflector or baffle 14 which is located in position within the case by a securing screw 15 the deflector conforming to the arcuate shape of the casing and being itself of such a cross-sectional shape as to provide a passage 16 to allow liquid to pass upwardly from the lower part of the pump casing to the pressure branch or pump outlet 4, the deflector being cut away at its upper end or so disposed with respect to the interior of the pump casing to provide an opening 17 for the escape of air or vapour past the upper edge of the deflector and out of the pump outlet. The deflector is shown in the form of a separate unit but it may alternatively form part of the pump casing.

As some leakage of water from the body into any part of the passage is permissible, the deflector or baffle need not be fitted closely to the side of the pump body but may for example be an un-machined casting shaped approximately to fit the body.

The outlet 4 is situated above the pump mechanism so that when the pump is at rest, liquid is trapped in the casing but when the pump is running, any solid matter which might accumulate at the bottom of the casing will be caused to pass upwardly along the passage formed by the deflector and out of the outlet connection. The deflector also has the effect of preventing stagnation of the liquid in the pump casing while also as previously stated providing for the escape of air or vapour from the upper part of the casing.

In the modified construction shown in Figure 2 the passage 16 is externally arranged and takes the form of an external pipe 18 connecting the lower part of the pump casing with an extension 19 on the outlet pipe 4, the passage providing an escape for solid matter while the bulk of the liquid and any air or vapour will be forced into the outlet pipe direct from the pump casing, the outlet connection being again situated above the pump mechanism.

In Figure 3 is shown an arrangement particularly suitable for use as a combined liquid pump and air or gas compressor or as a pump delivering liquid into a receiver or tank for storage, the pump mechanism being contained within a tank or receiver 20 of comparatively large size which tank or receiver fulfils the function of the pump casing. For example, the lower part of the receiver may contain pump working parts wholly or partly submerged in liquid, the upper part of the receiver acting as a receiver for the gaseous fluid. In this arrangement an external pipe 18 is again provided, forming a passage 16 connecting the lower part of the receiver with a point above the level of the liquid in the receiver when the pump is stationary. An escape pipe is provided for the outflow of air or vapours, the pipe taking the form of a small diameter branch connection 21 leading into the pipe 18.

In the constructions hereinbefore described, the minimum cross-sectional area of the passage 16 including its points of connection with the pump casing or receiver is such that sufficient velocity of liquid flow through the passage 16 will prevent the deposition of solids therein which might otherwise tend to clog the passage and prevent efficient operation of the pump.

Although the invention has been described as applied to a pump of the kind forming the subject of my British Patent No. 592,432 wherein rotation of the eccentric or eccentrically enlarges and reduces the internal volume of the parts of the displacement chamber or chambers to suck in liquid from the suction side of the pump chamber and force it under pressure into the pressure chamber or receiver by way of the ports which are opened and closed as a result of movement of the displacement chamber or chambers in a vertical plane, the invention is applicable to any other suitable construction of pump of the non-centrifugal type.

What I claim is:

1. In a pump for delivering liquids having a casing, inlet and outlet connections leading to and from said casing and situated above the normal level of liquid in said casing when the pump is stationary, pumping elements for forcing liquid

entering said inlet connection, out through said outlet connection by way of said casing, a by-pass connection leading from the bottom of said casing to said outlet connection for the passage of a proportion of the pumped liquid together with any solid matter which might otherwise accumulate in the lower part of the pump casing.

2. A pump of the non-centrifugal type for delivering liquids, comprising, in combination, a pump casing forming a pressure chamber, non-centrifugal pumping elements mounted in said casing and open to said chamber for forcing liquid into the pressure chamber, an outlet from the casing disposed above the level of said pumping elements to retain liquid in said chamber around said elements, means forming a passage extending upwardly between the lower part of the pressure chamber to the outlet, whereby to permit the upward flow of at least a part of the liquid and any solid matter which might otherwise accumulate in the lower part of the pump to the outlet, and means forming a second passage extending between the upper part of the pressure chamber and the outlet at substantially the same level as the outlet, whereby to permit the escape of air or vapour from the upper part of the pump casing to the outlet.

3. A pump, as claimed in claim 2, wherein the first-mentioned passage forming means comprises an externally arranged pipe connecting the lower part of the chamber with the outlet connection, and said second-mentioned passage forming means comprises a pipe extending laterally from the chamber to said outlet connection.

4. A pump, as claimed in claim 2, wherein said chamber comprises a receiver of comparatively large dimensions, said first-mentioned passage forming means comprising a pipe arranged externally of the receiver and connecting the lower part of the receiver with the outlet connection and said second-mentioned passage forming means comprising a transverse pipe connecting the receiver and the outlet connection above the level of the liquid in the receiver.

5. A pump, as claimed in claim 2, wherein said second-mentioned passage forming means defines a passage above the bottom of said outlet connection.

6. A pump, as claimed in claim 2, wherein said first-mentioned passage forming means comprises a deflector mounted in the chamber in spaced relation to a side wall thereof, said second-mentioned passage forming means comprising the top of said deflector and the top of said chamber casing, the top of said deflector being positioned below the level of the top of said outlet connection and spaced from the top of said chamber to form the second-mentioned passage.

FREDERICK WALTER MCCOMBIE.
